UNITED STATES PATENT OFFICE.

GILBERT F. HELSON, OF BAYSIDE, NEW YORK, ASSIGNOR TO E. R. DURKEE & CO., OF NEW YORK, N. Y., A FIRM.

CARTON FILLING AND SEALING MACHINE.

1,277,928.

Specification of Letters Patent. Patented Sept. 3, 1918.

Application filed April 9 1918. Serial No. 227,429.

To all whom it may concern:

Be it known that I, GILBERT F. HELSON, a subject of the King of Great Britain, but having declared my intentions of becoming a citizen of the United States, residing at Bay Side, in the county of Queens and State of New York, have invented an Improvement in Carton Filling and Sealing Machines, of which the following is a specification.

My invention relates to machines for filling and sealing cartons, and its several objects are, to economize space; to provide means for holding the cartons and carrying them in the same plane over the bed of the machine; to provide means for first folding and sealing the bottoms of the cartons while being carried forward; to provide means for filling the cartons after their bottoms have been folded and sealed; to provide means for folding and sealing the tops of the filled cartons, and to provide means for discharging the completed packages from the holders and delivering the same to an attendant for packing.

The details of the invention are herein-after particularly described, and illustrated in the accompanying drawings, forming a part hereof, in which—

Fig. 1 is an elevation of the feed side of the machine.

Fig. 2 is a plan.

Fig. 3 is a detail partly in section, of the sprocket chain and adjustable bearing at the feed and delivery end of the machine.

Fig. 4 is a detail illustrating the means for folding the bottom end flaps, and spreading and glueing the bottom side flaps of the cartons.

Fig. 5 is a detail plan view of the lower gluer and means for folding the bottom side flaps after the glue has been applied to them.

Fig. 6 is a detail plan view of the bottom end flap closing and side flaps spreader plate.

Fig. 7 is a plan of the top flap folder and spreader, looking from the left hand side of the machine.

Fig. 7^a is an end view looking in the direction of the arrow Fig. 7.

Fig. 8 is a plan view of the mechanism for folding the end flaps at the top of the filled carton, and the spreader plate for the side flaps, looking from the left hand side 55 of the machine.

Fig. 9 is an elevation partly in section of the ejector and its operating cam, looking toward the left of Fig. 1.

Fig. 10 is an elevation of the pusher and 60 its operating cam, looking from the left side of the machine.

Fig. 11 is an elevation of the gluer for the top side flaps of the filled cartons, looking from the left hand side of the ma- 65 chine.

Fig. 12 is a plan of the hopper cut-off and operating cam.

Fig. 13 is a plan of the lower cut-off.

Fig. 14 is a detail in vertical section illustrating the adjustability of the measuring chamber for the supply of filling material, and

Fig. 15 is a plan of the driving mechanism.

Similar reference characters denote like parts throughout the several views.

10 indicates the bed of the machine, supported by the posts 11, between which are the cross beams 12.

Supported at a predetermined distance above the bed 10, by standards 13, is a guide-frame comprising two vertically spaced parallel bars 14 and 15, extending longitudinally of the machine on each side thereof, and having semi-circular connections at each end of the machine, forming a continuous upper and lower guide bar. These two bars are each rigidly secured to the vertical members 13.

In the facing surfaces of the respective bars, there is a longitudinal groove 17, extending the entire length of their straight side portions, the outer wall of the groove being removed upon the semi-circular ends 95 to permit of the free passage of the guide plates hereinafter described.

18, denotes a sprocket chain, to the outer side of which are connected at equally spaced intervals, vertical guide plates 19, 100 in any suitable manner, preferably by means of short arms 20, and rivets 21.

These plates 19, are comparatively narrow in width, but are of such length that their upper and lower ends fit into the grooves 17 in the respective bars 14, 15, and 5 travel therein when the machine is in motion.

A carton holder 22, is secured to each of the plates 19 in any suitable manner. I have shown lugs 23, upon the carton holders, 10 which are held to the plates 19 by screws 24.

The carton holders are open at both top and bottom, and are of a shape corresponding to the shape of the body of the cartons in their expanded form, and are preferably 15 slightly flared at the top to facilitate the insertion of the cartons.

25, indicates a sprocket wheel horizontally disposed and keyed to a vertical shaft 26, adjacent its upper end.

20 This sprocket wheel is located at the feed and delivery end of the machine, and engages the chain 18, at that end of the machine.

The ends of the vertical shaft 26, are journaled in bearings 27 and 28, slideable in longitudinal grooves 29, in blocks 30, and 31; the block 31 being secured to the upper guide bar 15, and the block 30, to the bed 10. These bearings are adjustable by means of 35 the screws 32.

There is another sprocket wheel 33, at the other end of the machine, similar to the wheel 25, which engages the chain 18 at that end. This sprocket wheel 33 is fixed to 35 the vertical shaft 34, near its upper end, which end is journaled in a fixed bearing secured to the upper guide bar 15. The lower end of this vertical shaft is journaled in a bracket bearing 35, secured to the lower 40 part of the frame of the machine.

Keyed to the lower part of the shaft 34, is a bevel gear 36, meshing with a bevel gear 37, keyed to the transverse shaft 38, the ends of which are journaled in bearings in the 45 ends of the brackets 39, secured to one of the posts 11, of the frame.

There is also a sprocket wheel 40 keyed to the transverse shaft 38.

41, indicates a motor upon the shaft 42, 50 of which is keyed a gear wheel 43, which meshes with a gear wheel 44, keyed to the shaft 45, upon the outer end of which is fixed a pulley 46.

47, denotes another pulley of larger diameter, which is fixed to a transverse shaft 48, journaled in bearings in two of the frame posts 11. 49, is the drive belt passing over the pulleys 46 and 47.

Keyed to the shaft 48, is a gear 50, meshing with a gear 51, keyed to a transverse shaft 52.

53, is another transverse shaft, journaled in hangers 54, secured to the underside of the bed 10. Upon this shaft is fixed a 55 sprocket wheel 55 from which passes a

sprocket chain 56, connected with a sprocket wheel 57 fixed to the shaft 52.

Securely fixed to the outer end of the shaft 53, is a short arm 58, upon the free end of which is secured a pin 59, extending outwardly at right angles.

At a predetermined distance from the shaft 53, parallel therewith on the same plane, is another transverse shaft 60, journaled in hangers 61, secured to the underside of the bed 10.

On the outer end of this shaft 60, is keyed a star-wheel 62, provided with four equally spaced radial slots 63. 64, is a gear wheel keyed to the shaft 60, between which and the sprocket wheel 40, on the shaft 38, passes a connecting sprocket chain 65.

The short arm 58, on the shaft 53, is so positioned that when the shaft 53, revolves, the pin 59 will enter the slots 63 in the star wheel 62, imparting movement to the star wheel so long as the pin remains in and engages the wall of the slots, and as the pin emerges from the slots the star wheel comes to rest, therefore the shaft 60, is given one quarter of a revolution at each complete rotation of the shaft 53, which imparts a similar motion to the vertical shaft 34, through means of the sprocket wheels 64 and 40, sprocket chain 65, and bevel gears 36 and 37, whereby the sprocket chain 18 is given an intermittent movement, carrying the carton holders 22, forward a pre-determined distance at each movement of the star wheel 62.

The feed operator is stationed on the right 10 of the machine at its left hand end, and as the carton holders pass that point, the cartons 66, in expanded form and with both top and bottom flaps extended vertically, are inserted within the carton holders and 11 carried forward by the sprocket chain 18.

There is a plate 67, located below the carton holders 22, at this point, spaced from the lower open end of the carton holders a distance equal to the length of the extended 11 lower flaps of the cartons, and upon which the ends of such flaps rest when the cartons are placed in the holders. This assures the proper positioning of the cartons within the holders, as the plate forms a stop for 12 the downward movement of the cartons. The plate 67 is supported by standards 68, secured to the bed 10, and extends longitudinally of the machine a predetermined distance.

69, indicates another horizontal plate extending a certain distance longitudinally of the machine, its left hand end being tapered. This plate is supported below the guide bar 14, in any suitable manner; I have shown 12 angle irons 70 for this purpose. The plate 69, is located to the right of the plate 67, at a predetermined distance therefrom, and nearer to the bottoms of the carton holders.

After the lower extended end flaps of the 13

carton pass off the plate 67, and approach the plate 69, the front end flap of the carton contacts with the tapered end of the plate 69, by which it is folded inward of the carton, 5 and at the same moment the lower rear end flap of the carton is also folded inward by a swinging folder arm 71, operated by the means next described.

The lower end of the arm 71, is pivotally 10 secured to a bifurcated lug 72 by a pivot pin 73, said lug being secured to the top of the bed 10. 74, is a vertical shaft, its lower end being journaled in a bearing block 75 and having an upper support secured to 15 the bar 14. Keyed to the shaft 74, at about its center is a hub 76, having an integral projection or lug 77. Surrounding the shaft 74, between the hub 76, and the bearing block 75, is a spiral spring 78, one end of 20 which is secured to the stationary bearing 75, the other end being secured to said hub. 79, denotes another bifurcated lug secured to the top of the bed 10, in which is pivotally secured one end of a link 80; the 25 other end of said link being pivotally connected to one end of a longer link 81, which at its other end is pivotally connected to the arm 71.

82, is a connection rod between the lug 30 77, on the hub 76, and the link 80, having a pivotal connection with each of these members. 83, is an arm extending at right angles from the shaft 74, one end being keyed to said shaft at its top. A wheel 84, is attached to the free end of the arm 83, by a pivot pin 85. The wheel 84, comes into contact with the rear surface of a passing carton holder, which forces the wheel away from the holder, thereby giving the shaft 35 74, a partial rotation, contracting the spring 78 and by means of the connection rod 82, and links 80 and 81, the folder arm 71 is drawn up into a vertical position, during which movement its head strikes the lower 40 rear end flap of the carton contained in the holder, folding it inwardly. The forward end of the head of the arm 71 is preferably rounded, so that it will not injure the flap when striking it and will bear upon its surface 45 smoothly. As soon as the wheel 84, loses contact with the carton holder, the compression on the spring 78, is released thereby allowing it to expand which throws the "kicker" or folder arm 71, back to its 50 normal position, until the next carton holder contacts with the wheel 84, when the arm 71, will again be operated as before, which action is repeated so long as the machine is being operated. The details of this mechanism 55 is most clearly illustrated in Fig. 4 of the accompanying drawings.

As the carton holder advances, the two folded lower end flaps of the carton contained therein, ride upon the plate 69, as 60 do also the two lower side flaps, but in conse-

quence of the broadened width of the plate 69, to the rear of its tapered end, these two side flaps are spread outwardly into horizontal position while passing over the upper surface of said plate. 70

Adjacent the rear end of the spreader plate 69, there is a glue roller 86, mounted upon a transverse shaft 87, journaled in bearings 88, secured to the top of the side walls of a glue receptacle 89, which is seated 75 upon and secured to the bed 10, in any suitable manner.

Upon the inner end of the shaft 87, there is fixed a sprocket 90.

91, is another transverse shaft in vertical 80 alinement with the shaft 87, upon which there is fixed a sprocket 92, in the same alinement with the sprocket 90. A chain belt 93, passes over and connects these two pulleys. The shaft 91 is journaled in bearings 94 secured to the underside of the bed 10.

95, is another transverse shaft spaced from and parallel with the shaft 91, on the same plane and journaled in similar bearings 96. 90 A sprocket chain 97, passes between the shafts 91 and 95, and engages a sprocket wheel keyed to each of said shafts.

98, is a sprocket wheel keyed to the shaft 95, and 99, is a similar wheel keyed to the 95 shaft 53; a sprocket chain 100 passes over and engages these respective wheels. By means of these sprocket and chain connections the glue roller 86 is continuously revolved while the motor 41 is operated. 100

When the outwardly spread lower side flaps of the cartons reach the rear end of the spreader plate 69, they pass over the periphery of the glue roller 86, and receive a thin coating of glue upon their under surfaces. As these horizontally and outwardly spread side flaps pass off the glue roller, they are engaged by a pair of folding members 101 and 102, which are so disposed with relation to each other that one of the side 105 flaps is first folded over upon the top of the previously folded end flaps, to which it adheres by its coating of glue, and then the opposite and remaining glued side flap is folded over upon the top of the first folded 110 side flap, thus completely sealing the bottom of the empty carton. 115

These folding members 101 and 102, are curved in such manner as to turn the side flaps over and press the same against the 120 previously folded flaps.

The member 101 is supported by an upright 103, secured to the top of the bed 10, while the member 102 is secured to the guide bar 15, by screws or rivets 104. 125

To prevent any possibility of the cartons being pushed up in the holders, during the folding and sealing of the bottom flaps, I provide a comparatively narrow flat strip 105, which is secured along one edge to the 130

top of the bar 15 by rivets or screws or in another suitable manner, and projects slightly over the side of said bar for a predetermined distance. That end of this strip 5 nearest the approaching carton holders is bent slightly outward from the bar 15, and curved in such manner that its free end first contacts with the front top end flap of a carton and then with the inner side flap 10 which it turns outward and guides under the strip 105, where such flap travels during the folding and sealing of the bottom flaps of the carton, after which said flap passes from under said strip and assumes a vertical 15 or nearly vertical position; it is not creased by said strip but merely held with sufficient top pressure to prevent the carton rising in the holder while the bottom flaps are being acted upon, and springs back to its first 20 position, as does the end flap when released from the strip 105.

106 is an elongated plate, supported by the standards 107, secured to the top of the bed 10. This plate is located adjacent to and in 25 alinement with the folding members 101 and 102, so that when the cartons pass the side flap folders their folded and sealed bottoms ride upon said plate, from which they pass upon another support 108, which is 30 supported from the bed 10, by uprights 109. This member 108 extends along the other side of the machine for a greater distance, being curved to conform to the end curvature of the guide bars 14 and 15, and is 35 preferably composed of a flat strip, in order to prevent interference with the working of the filling and measuring mechanism at this end of the machine. These supports 106 and 108 for the folded and sealed bottoms of the 40 cartons, assure the thorough setting or drying of the paste or glue before the cartons pass off said support 108.

The movement of the star wheel 62, is so timed that at each time it comes to rest, one 45 of the carton holders 22, containing one of the cartons 66 with its bottom flaps folded and sealed, has been brought directly under and in register with a funnel 110, containing a measured quantity of the filling material 50 which is discharged into such carton, the next movement of the sprocket chain 18, carrying said filled carton past the filling funnel and bringing the next carton holder with its contained carton in register with 55 said funnel, and so on continuously while the machine is being operated.

The details of the measuring and filling mechanism will be next described.

111, denotes a hopper for holding the filling material 112, to be supplied to the cartons. This hopper is supported at the right hand end of the machine, a predetermined distance above the bed 10, by and between two posts 113, the lower ends of which are 60 bolted or otherwise fastened to the bed, one

adjacent each side at this end of the machine. The upper ends of the posts 113, are secured to the ends of the arms 114, projecting from the hopper at opposite sides, by bolts 115.

70 116, indicates a vertical shaft, supported at its upper portion in bearings within a sleeve 117, to which is secured one end of a horizontal bar 118, the other end of which is secured to a yoke 119, connecting the posts 75 113. This shaft 116, also has a bearing beneath the bed 10, in a bracket 120, secured to the underside of the bed.

Keyed to the bottom end of the shaft 116, 80 is a bevel gear 121 which meshes with a bevel gear 122, keyed to the longitudinal shaft 123, the ends of which are journaled in the hangers 124, and 125, secured to the underside of the bed. There is a bevel gear 126 keyed to the shaft 123, which meshes with a 85 bevel gear 127, keyed upon the inner end of the transverse shaft 53. It will therefore be seen that the longitudinal shaft 123, will be continuously rotated while the motor is running, as will also the vertical shaft 116. 90

Upon the upper end of the shaft 116, is fixed a small bevel gear 127', which meshes with a similar gear 128, fixed upon one end of a horizontal shaft 129 rotating in bearings 130, 131, supported by the member 132 95 at the top of the hopper 111, to which it is secured by rivets 133.

The member 132, has an integral horizontal arm 134, extending to the center of the hopper 111, and is provided at the end with 100 a hole through which extends the upper end of a vertical shaft 135, fitted in a bearing 136, and having secured to its lower end a plurality of agitator blades 137. Upon the extreme upper end of the shaft 135, is keyed 105 a small bevel gear 138, which meshes with a similar gear 139, upon the other end of the horizontal shaft 129. It will thus be seen that the agitator shaft 135 and blades 137 will be continuously rotated during the rotation of the vertical shaft 116.

The hopper 111 is preferably tapered from top to bottom, and at a certain distance from its bottom is provided with an integral horizontal projection 140, which 115 extends on one side in substantially rectangular form for a predetermined distance.

Bearing against the under surface of the plate or projection 140, and of like shape therewith is another plate 142; the two 120 plates being secured together around their outer edges by screws or bolts 143. The plate 142 is provided in its upper surface with a longitudinal groove or recess 144, within which is slidably fitted a shut off 125 plate 145, there being a slot 146, in one side of the hopper 111, through which said shut-off plate may pass. This shut-off plate is connected to one end of a rod 147, which passes through an opening in the plates and 130

a boss 148. Secured to two vertical guide members 141, arranged at either side of the plates 140 and 142, is an angle piece 149, there being a vertical slot in the upright end 5 portion of said angle piece through which the rod 147 passes. The other end of said rod extending through a hole in the upright support 150, the flanged lower end of which is bolted to the bed 10. There is a 0 collar 151, keyed to the rod 147, and between this collar and the upright end of the angle piece 149, there is a spiral spring 152, surrounding the rod 147.

A stop nut 153 upon the rod 147, limits 5 the movement of the rod between the boss 148, and angle piece 149.

Upon the extreme end of the rod 147 there is fixed a pair of jaws 154, between which a wheel 155 is pivotally secured by a pivot 10 pin 156.

157, indicates a cam keyed to the vertical shaft 116, at a point in alinement with the rod 147. This cam contacts with the wheel 155, each revolution of the shaft 116 15 pressing the spring 152, and pushing the cut-off plate 145 through the slot in the side of the hopper, thus shutting off the discharge of the filling material from the hopper, until the cam passes off the wheel, when 30 the shut-off plate is withdrawn from the hopper by the expansion of the spring 152, allowing the discharge of the filling material to proceed until again shut off by the contact of said cam with said wheel.

35 When the shut-off plate 145 is in the position shown in Figs. 1 and 12, it may be retained in such position for any desired length of time, whether the machine is in operation or at rest, by means of the latch 40 158, one end of which is hinged or pivotally connected to the bar 118, and can be swung down behind the collar 151 as illustrated in dotted lines, preventing any movement of the rod 147, while it is thus positioned.

45 159, is another upright having its flanged lower end bolted to the bed 10, and provided with a right angled top 160, extending to the upright 150, to which it is secured by bolts or rivets 161 or in any suitable manner. There is a circular opening in the horizontal member 160, through which the vertical shaft 116, passes.

The extreme lower end of the hopper 111, is outwardly flared or flanged as at 162, (see 50 Fig. 14), and is fitted within an interior annular groove 163, in the top of a measuring chamber 164, provided with ears or lugs 165 on its exterior.

This chamber 164 is cylindrical, and about 55 midway of its length the lower portion is somewhat contracted, and provided with a screw thread on its exterior, which connects with an interiorly threaded portion of a short tubular member 166.

60 At the lower end of this tubular section,

there is an integral horizontal projection 167, similar to the projection or flange 140, on the lower part of the hopper 111, and in vertical alinement therewith and spaced a predetermined distance therefrom. 70

The lower ends of the vertical guide members 141 are secured to this plate 167.

168, denotes a vertical tube in register with the tubular section 166, and having at its upper end an integral horizontal projection or plate 169 of like shape to the projecting member 167 upon the member 166, the plate 169, bearing against the under surface of the plate 167, the two plates being secured together by bolts or screws 170, 80 around their outer edges.

The plate 169, is provided in its upper surface with a longitudinal groove or recess 171 extending from the outer end of said plate to the interior of the tube 168. 85

Slidably fitted within this recess or groove is a cut-off plate 172, connected to a hub 173, upon one end of a horizontal rod 174. This rod passes through a vertical slot in the upright 150, and has a bearing 175, in the upper end of a vertical member 176, secured to the upright 150, by a bolt 177, which passes through said vertical slot in the upright, said rod and bolt being capable of vertical movement in such slot. 95

The end of the rod 174, projecting beyond the upright 150, is fastened to the vertical inner end 178 of a horizontal plate 179, in which there is a central longitudinal slot 180, through which the vertical shaft 116 100 passes. At the outer end of the plate 179, and extending downwardly from its underside, is connected a roller 181, by a pivot pin 182.

Surrounding the rod 174, between the bearing 175 and hub 173 and connected at its respective ends therewith, is a spiral spring 183.

184, indicates a cam keyed to the vertical shaft 116, immediately beneath the plate 110 179, which cam contacts with the roller 181, at each revolution of the shaft 116.

The action of the cams 157, and 184, on the respective cut-offs are the reverse of each other, that is, when the cam 157, contacts 115 with the wheel 155, it compresses the spring 152, and forces the cut-off plate 145, into the hopper, shutting off the feed of filling material, and when said cam passes off said wheel the spring 152 expands withdrawing 120 the shut-off plate and thereby renewing the feed, whereas in the lower cut-off when the cam 184, contacts with the roller 181, the rod 174 is drawn outwardly, the spring 183, expanded and the cut-off plate 172, with- 125 drawn from the tube 168, and when the cam passes off said roller, the spring 183, contracts, pushing the cut-off plate 172, back over the top of the tube 168, and closing the bottom of the tubular member 166. 130

The cams 157, and 184, are positioned upon the shaft 116, so that the respective shut-offs are operated alternately, that is, when the upper one is closed, the lower one 5 is open, and when the lower one is closed, the upper one is open.

The details of the lower cut-off are most clearly shown in Fig. 13, of the drawings.

The vertical tube 168 extends into a 10 cylinder 185, through a short tube 206, projecting at the top of the cylinder which is secured to the plate 169, and the lower open end of said tube is in alignment with the open top of the funnel 110, which funnel is 15 located within said cylinder, being secured to one end of a lever 186, fulcrumed at 187, outside said cylinder, said lever passing through a vertical slot in that side of the cylinder, which slot is open at the bottom 20 as is the bottom of the cylinder.

The other end of the lever 186, is pivotally connected to the upper end of a vertical rod 188, which is located within a tube 189, the bottom of which is secured to the top of 25 the bed 10.

Surrounding the rod 188, within the tube 189, is a spiral spring 190. The rod 188, extends through an opening in the bed, and its extreme lower end is bifurcated within 30 which is secured a wheel 191, by a pivot pin 192.

193, indicates a cam keyed to the shaft 123, at a point in line with the lower end of the rod 188, which cam contacts with the 35 wheel 191, as the shaft 123 is revolved, thereby forcing the rod 188, upward against the action of the spring 190, raising the outer end of the lever 186 and lowering the funnel 110, at the other end of the lever into 40 the position shown in Fig. 1. As the cam 193, passes off the wheel 191, the spring 190 contracts, drawing the rod 188 downwardly, which elevates the funnel 110 a certain degree within the cylinder 185. This occurs 45 while the cam 184 is acting upon the wheel 181, which withdraws the cut-off plate 172, from between the tubes 166 and 168, allowing a measured quantity of the filling material contained in the measuring chamber 50 164, to discharge into the funnel, the upper cut-off in the bottom of the hopper 111, being at the same time closed by the action of the cam 157, on the wheel 155. When the cam 193 again contacts with the wheel 55 191, the funnel is lowered with its contents directly over the open top of one of the cartons 66, which at that moment has come to rest in such position, while the lower cut-off has been closed, and the upper cut-off 60 opened by the action of the respective cams 184 and 157.

The quantity of filling material to be delivered into the cartons, is regulated by rotating the measuring chamber 164, which 65 may be readily done by hand, the lugs or

ears 165, being preferably provided on the exterior of such chamber or facilitating this operation. By the rotation of the chamber 164, in one direction the tube 168, is drawn upward, and when said chamber is rotated in 70 the reverse direction, said tube is lowered; such movements, of course, also either raise or lower the plates 167 and 169 with the cut-off plate 172, and parts connected therewith, the rod 174 and its bearing moving in the 75 vertical slot in the upright 150, while the guide members 141 slide against the opposite sides of the plates 140 and 142. The roller 181, must be of such width that the cam 184, will contact with it at each revolution of the shaft 116, whether the lower 80 cut-off is in a raised or lowered position.

The continued intermittent motion of the sprocket chain 18 carries the carton holders containing the filled cartons to the other 85 side of the machine with the sealed bottoms of the cartons still riding upon the supporting strip 108, which is extended on that side of the machine a distance to support the filled cartons while their top flaps are 90 being folded and sealed.

194, indicates another folder and spreader plate, similar to the plate 69, on the other side of the machine, as heretofore described. The plate 194, is secured to the 95 top guide bar 15, in any suitable manner, and its tapered end in the direction of the approaching carton is preferably slightly curved upwardly so that the first top end flap of the carton with which it contacts is 100 folded inwardly and downwardly under said plate, and as the carton advances its side flaps are spread outwardly by said plate at right angles to the vertical walls of the car- 105 ton.

As the carton holder passes beneath the plate 194, it comes into contact with a wheel 195, which bears upon the outer surface of the inner side wall of the carton.

This wheel is pivotally connected in a 110 horizontal position to one end of a short arm 196, extending from a hub 197, keyed to the top of a vertical shaft 198, which is rotatable in an upper bearing secured to the rail 14, and has a bottom pivotal bearing at 115 199. That portion of the shaft 198, below the rail 14 is surrounded by a spiral spring 200, the lower end of which is secured to the bearing 199, and its upper end to the shaft.

The contact of the wheel 195, with a car- 120 ton holder forces the wheel outward from the carton, thereby moving the arm 196, and partially rotating the shaft 198, against the action of the spring 200. Integral with 125 the hub 197 there is another arm 201, ex- tending at right angles to the arm 196 and of somewhat greater length than that arm.

202, is another vertical shaft spaced a cer- 130 tain distance from the shaft 198, its lower

end being fixed at 203, upon the top of the bed 10, and its upper end fixed in a bracket 204 fastened to the rail 15, by a bolt 205.

207, is a kick lever, fulcrumed upon the 5 shaft 202, the rear arm 208, of said lever being pivotally connected to a link 209, the other end of said link being pivotally connected with the other end of the arm 201. The free end of the lever 207, is provided 10 with a toe 210, the end of which is preferably rounded as shown. (See Fig. 8.)

At the same time that the folder and spreader plate 194, is folding inward one 15 end flap, and spreading the two side flaps of a filled carton, the wheel 195, is in contact with one side of the carton holder containing said filled carton, whereby through the action of the arms 196 and 201, and link 209, the kick-lever is swung into the position 20 shown in broken lines in said Fig. 8, coming into contact with the other end flap of said carton and folding it inward as illustrated in broken lines in said Fig.

When the wheel 195 passes off said carton 25 holder, the lever 207, is drawn back to its normal position shown in full lines in said Fig. 8, by the contraction of the spring 200. The outwardly spread side flaps of said 30 filled carton pass from the rear end of the spreader plate 194, under a glue roller 211, mounted upon a shaft 212, which is journaled in brackets 213, secured upon the top of the bed 10, by bolts 214. 215, denotes a glue reservoir, supported upon a bracket 35 216, secured to the brackets 213 by bolts 217. This glue reservoir has an open concave end adjacent the glue roller 211, which the glue roller closes.

There is an adjustable bottom plate 218, 40 fitted in the glue reservoir, the front edge of which plate is preferably beveled and is adapted to engage the surface of the glue roller, or to be adjusted to any desired degree of proximity thereto, by means of the 45 adjusting screw 219. This plate is held in the position to which it may be adjusted by means of the clamping nuts 220. There is a sprocket wheel 224, keyed upon the glue roller shaft 212, from which passes a 50 sprocket chain 225, connecting with a sprocket wheel 226, keyed upon the shaft 95, whereby the glue roller 211, is continuously revolved while the machine is in operation. As the outwardly spread side flaps 55 pass from under the glue roller, they are engaged by a pair of folding members 221 and 222, similar to the folders 101 and 102, on the opposite side of the machine and hereinbefore described, and act upon the 60 side flaps at the top of the carton, in the same manner that the others act upon the side flaps at the bottom of the cartons, that is, these folders 221 and 222, are so disposed with relation to each other that one of the 65 side flaps is first folded over upon the top of

the previously folded end flaps to which it adheres by the glue it received from the glue roller, and then the opposite and remaining glued side flap is folded over upon the top of the first folded top side flap, thus 70 completely sealing the top of the filled carton. These folders 221, and 222, are connected at one end to the top bar 15 of the guide frame.

The sealed cartons as they leave the fold- 75 ers 221 and 222, are carried under an elongated flat strip or plate 223, fastened along one edge to the top bar 15, by rivets or in any suitable manner. This plate holds down the last fold of the side flaps for a certain 80 distance to assure the setting or drying of the glue. Adjacent that end of the plate 223, where the filled and sealed cartons pass from under it, there is provided means for 85 ejecting the filled and sealed cartons from their holders, which will next be described.

227, denotes a tubular standard, having a base 228, seated upon the top of the bed 10, to which it is secured by bolts 229. There 90 is an opening 230, through the bed immediately below the base of the standard.

Projecting at right angles from the top of said standard and integral therewith, is an arm 231.

232, is a vertical rod within said standard, 95 its lower end passing through said opening in the bed, and extending below the bed, a predetermined distance.

233, is a spiral spring surrounding said rod inside said tubular standard, its lower 100 end bearing against the base of the standard surrounding a hole therein through which the rod 232 passes. There is a collar 234 secured to the upper part of the rod within the tubular standard against the under surface of which the upper end of said spring bears.

There is a horizontal arm 235, extending 105 parallel with the arm 231, one end of said arm 235, being secured to the top of said rod 232. 236, is a vertical plunger rod, secured at its upper end to the free end of the arm 235, by a nut 237, screwed upon the upper threaded end of the plunger rod which passes through a hole in the end of 115 the arm 235.

The lower end of the plunger rod is provided with a flat head 238, shaped preferably similar to the interior shape of the carton holders 22, and adapted to slide up 120 and down loosely therein. The lower end of the rod 232, is flattened and provided with an opening.

239, is a flat link to the upper end of which the lower end of the rod 232, is pivotally 125 connected by a pivot pin 240. The lower end of the link 239 is folded upwardly, and within such fold one end of an arm 241, is pivotally secured by a bolt 242, the other end of said arm being pivotally secured to 130

- a bracket 243, by a bolt 244. To one side of the arm 241, at or about its center, there is pivotally fastened a wheel 245, by a bolt 246. 247, indicates a cam keyed to the longitudinal shaft 123, which cam contacts with the wheel 245, on the arm 241, at each revolution of the shaft 123, whereby the rod 232, and plunger 236, are drawn downward, compressing the spring 233, which expands when 10 the cam 247, passes off the wheel 245, forcing the rod 232, and plunger upward into their normal positions, in which the plunger head 238, is slightly above the top of the carton holders, and the actions of the cam 247 and 15 spring 233, are such that the plunger head occupies this raised position just as the intermittent movement of the sprocket chain 18, has brought one of the carton holders 22, containing a filled and completely sealed 20 carton at rest directly under and in alignment with the plunger head, and during this interruption in the movement of the chain 18, the cam 247, again contacts with the wheel 245, drawing down the plunger head 25 238, upon the top of the filled carton and within the holder containing such carton, whereby the carton is pushed out of the holder through its open bottom and deposited upon the bed 10, after which the 30 plunger is raised out of the top of the holder by the action of the spring 233, into a position to act upon the next carton in the same manner. The details of the ejector are most clearly illustrated in Fig. 9 of the drawings. 35 As soon as one of the filled and sealed cartons is ejected from its holder and deposited upon the bed of the machine as just described, it is struck on one side by a pusher 248, which pushes it forward upon the bed 10, a distance of about the width of one of the carton holders, so that the next ejected carton will be deposited upon the bed closely 40 adjacent to it, and will push the first carton forward again the same distance when 45 said second carton is struck and carried forward by said pusher, the filled and sealed cartons being moved forward in succession in this manner into a delivery chute 249, from which they are taken by an operator 50 on this side of the machine and packed for transportation. The delivery chute 249, is formed by two flat side strips 250, equally spaced longitudinally, and supported by angle pieces 251, secured to the bed 10. 55 The details of the pusher mechanism are most clearly illustrated in Fig. 10 of the drawings, and will now be described.
- The lower part of the vertically disposed pusher plate 248, is connected to one end of a horizontally disposed arm 252, the other end of said arm being rigidly secured by bolts or rivets 253, to the upper end of a longer arm 254, vertically disposed, which extends through a slot 255, in the bed 10. 60 65 256, is a bracket, secured to the underside of the bed 10, by bolts 257. The lower end of the arm 254, is pivotally connected to the lower tapered end of the bracket 256, by a pivot pin 258. There is another bracket, similar to the bracket 256, and in transverse alignment therewith. 259 is a transverse shaft journaled in bearings in said brackets 256.
- Upon one end of this shaft 259, there is keyed a bevel gear 260, which meshes with a similar bevel gear 261, keyed upon the longitudinal shaft 123, by means of which the shaft 259 is rotated. Keyed upon this shaft 259, is a cam 262, which upon each revolution of the shaft 259, contacts with a wheel 263, pivotally connected to one side of the arm 254, by a bolt 264. Each time the cam 262, acts upon the wheel 263, the arm 254, is swung outward on its pivot pin 258, carrying the pusher plate 248, forward. When 25 the cam passes off the wheel, the arm 254, and pusher plate, are drawn back in their normal positions by the contraction of a spiral spring 265, one end of which is connected to said arm, its other end being connected to a stud or pin 266, secured upon the underside of the bed 10, which spring had been expanded when the arm 254, was forced forward. 30 35 40 45 50 55 60 65 70 75 80 85 90 95 100 105 110 115 120 125 130
- I prefer to provide the top end plates 267, to cover the sprocket wheels 25, and 33, for protection of the operators, and to exclude dust or other foreign substance.
- 268 is a funnel-shaped basin fixed into an opening in the end of the bed 10, in vertical alignment with the funnel 110, which basin is for the purpose of catching any spilled filling material or overflow, in order to prevent waste of such material. This basin communicates with a tube 269, below the bed 10, which tube enters the top of a box or suitable receptacle 270 in which any spilled filling material or overflow is collected.
- My improved machine economizes in floor space; the cartons are carried in the same horizontal plane during the entire operation of folding and sealing the bottom flaps while the cartons are empty; providing for the setting or drying of the glue, filling the cartons consecutively; folding and sealing the top flaps over the contents, setting or drying the glue applied to such flaps in the sealing thereof; ejecting the filled and completely sealed cartons in succession from their holders, and delivering them to an operator for packing. 110 115 120 125 130
- I claim as my invention:
1. In a machine of the character described, the combination of an endless conveyer, means for imparting an intermittent movement to the same, a series of equally spaced carton holders connected to one side of the conveyer, means for folding one end flap and spreading the side flaps at the bottom 130

- of a carton as its holder is advanced, means operated by contact with the moving carton holder for folding the other end flap at the bottom of the carton, means for applying glue to said spread side flaps, means for folding said glued flaps one upon the other, an elongated bearing for the bottoms of the cartons thus folded and sealed, means for discharging a measured quantity of filling material into such cartons in succession, means for folding one top end flap and spreading the two top side flaps, means for applying glue to said spread flaps, means operated by contact with the carton holder for folding the other top end flap, means for folding the two top glued side flaps, and means bearing upon said folded flaps while the glue is setting or drying.
2. In a machine of the character described, the combination of an endless sprocket chain, means for imparting an intermittent rotation thereto, a series of equally spaced carton holders connected to said chain, a folder and spreader plate by which one end flap is folded and the side flaps spread outwardly at the bottom of a carton as its holder is advanced, means for applying glue to the spread flaps, a swinging arm with link connections, and a wheel connected therewith, which wheel contacts with one side of the moving carton holder operating said arm to fold the other bottom end flap, a spring for drawing said swinging arm back to its normal position when the said wheel passes off the carton holder, means for folding said glued side flaps, an elongated bearing for the bottoms of the cartons thus folded and sealed, means for supplying a measured quantity of filling material into the cartons in succession, means for folding and sealing the top flaps of the filled cartons, and means for ejecting them from their holders.
3. In a machine of the character described, the combination of an endless sprocket chain, means for imparting an intermittent rotation thereto, a series of equally spaced carton holders connected to said chain, means for folding and sealing the bottom flaps of the cartons, means for supplying a measured quantity of filling material into the cartons in succession, a folder and spreader plate by which one end flap is folded and the side flaps spread outwardly at the top of a filled carton as its holder is advanced, a kick-lever with link connections and a wheel connected therewith which wheel contacts with one side of the moving carton holder and operates said lever to fold the other top end flap, a spring by which the kick-lever is drawn back to a normal position when the said wheel passes off the carton holder, means for applying glue to said spread flaps, means for folding said glued flaps, and means for ejecting the filled and sealed cartons from their holders.
4. In a machine for filling and sealing cartons, the combination of an elongated bed and supports therefor, a guide frame supported over said bed parallel therewith and extending longitudinally thereof on both sides and provided with longitudinal grooves, a sprocket wheel, a vertical shaft for the same, supported in adjustable bearings upon the bed and frame adjacent one end thereof, another sprocket wheel adjacent the other end of the frame, a vertical shaft for the same extending through a bearing in the bed, an endless sprocket chain connected with said sprocket wheels, a series of equally spaced guide plates loosely fitted into said grooves in the frame and secured to said chain on one side thereof, a series of carton holders attached to the respective guide plates, means for intermittently rotating said second sprocket wheel, means for folding and sealing the bottom flaps of the carton, means for supporting the cartons thus sealed, means for delivering a measured quantity of filling material into the cartons in succession, and means for folding and sealing the top flaps of the filled cartons, all while the cartons are intermittently moved above the bed in the same horizontal plane.
5. In a machine for filling and sealing cartons, the combination of an elongated bed and supports therefor, a guide frame composed of two horizontal parallel bars arranged one above the other in vertical alignment and provided with a longitudinal groove in their facing surfaces, said bars extending longitudinally of the bed on each side thereof and having semi-circular end connections forming a continuous upper and lower guide member, vertical supports for the same secured to each bar and at their lower ends to the bed, two sprocket wheels horizontally disposed, one adjacent each end within said frame, an endless sprocket chain connecting said sprocket wheels, a series of equally spaced vertical guide plates arranged between the upper and lower bars of said frame and fitted loosely within the grooves therein and connected with said sprocket chain, a series of carton holders provided with lugs secured to the respective plates, means for rotating said sprocket wheels intermittently, means for folding the bottom end flaps of a carton and spreading the lower side flaps thereof, means for applying glue to said spread flaps, means for folding said glued flaps, an elongated support for the bottom of the carton thus sealed, means for filling the carton with a measured quantity of filling material, and means for folding and sealing the top flaps of the carton after it has been filled.
6. In a machine of the character described, the combination of an endless sprocket chain, means for rotating the same

intermittently, a series of equally spaced carton holders connected to said chain, a folder and spreader plate by which one end flap is folded inward and the two side flaps 5 spread outwardly at the bottom of a carton as its holder is advanced, means for applying glue to the spread flaps, a swinging arm with link connections and a wheel connected therewith which wheel contacts with one 10 side of the moving carton holder operating said arm to fold the other bottom end flap, a spring for drawing said arm back when the said wheel passes off the carton holder, means for folding said glued side flaps, 15 an elongated bearing for the bottoms of the cartons thus sealed, means for supplying a measured quantity of filling material into the cartons in succession, a folder and spreader plate by which one end flap is 20 folded and the two side flaps spread outwardly of the top of each filled carton as its holder is advanced by said chain, a kick-lever with link connections and a wheel connected therewith which wheel contacts with 25 one side of the moving carton holder and operates said lever to fold the other top end flap, a spring by which the lever is drawn back when the wheel passes off the carton holder, means for applying glue to 30 said spread flaps, means for folding said glued flaps, and means for ejecting the filled and sealed cartons from their holders.

7. In a machine of the character described, the combination of an endless conveyer, means for imparting an intermittent movement to the same, a series of equally spaced carton holders connected to one side of the conveyer, means for folding one end flap and spreading the side flaps at the bottom of a carton as its holder is advanced, means operated by contact with the moving carton holder for folding the other end flap at the bottom of the carton, means for applying glue to said spread side flaps, 40 means for folding said glued flaps one upon the other, an elongated bearing for the bottoms of the cartons thus folded and sealed, means for discharging a measured quantity of filling material into such cartons in succession, comprising an elevated hopper, a cut-off acting therein, an adjustable measuring chamber connected with the lower end of the hopper, another cut-off acting to open and close the bottom of the measuring chamber, a delivery tube depending from such chamber, means for opening and closing the respective cut-offs in reverse order, a folder and spreader plate by which one end flap is 45 folded and the side flaps spread outwardly at the top of a filled carton as its holder is advanced, a kick-lever with link connections and a wheel connected therewith which 50 wheel contacts with one end of the moving carton holder and operates said lever to fold the other top end flap, a spring by which the kick-lever is drawn back to a normal position when the said wheel passes off the carton holder, means for applying glue to 55 said spread flaps, means operated by contact with the carton holder for folding the other top end flap, means for folding the two top side flaps, and means bearing upon said folded flaps while the 60 glue is setting or drying.

8. In a machine of the character described, the combination of an endless sprocket chain, means for imparting an intermittent rotation thereto, a series of equally spaced carton holders connected to 70 said chain, a folder and spreader plate by which one end flap is folded and the side flaps spread outwardly at the bottom of a carton as its holder is advanced, means for applying glue to the spread flaps, a swinging arm with link connections, and a wheel connected therewith which wheel contacts with one side of the moving carton holder operating said arm to fold the other bottom end flap, a spring for drawing said swinging 75 arm back to its normal position when the said wheel passes off the carton holder, means for folding said glued side flaps, an elongated bearing for the bottoms of the cartons thus folded and sealed, means for 80 supplying a measured quantity of filling material into the cartons in succession, comprising an elevated hopper, a cut-off acting therein, an adjustable measuring chamber connected with the lower end of the hopper, 85 another cut-off acting to open and close the bottom of the measuring chamber, a delivery tube depending from such chamber, means for opening and closing the respective cut-offs in reverse order, means for folding 90 and sealing the top flaps of the filled cartons, and means for ejecting them from their holders.

9. In a machine of the character described, the combination of an endless sprocket chain, means for imparting an intermittent rotation thereto, a series of equally spaced carton holders connected to 100 said chain, means for folding and sealing the bottom flaps of the cartons, means for supplying a measured quantity of filling material into the cartons in succession, comprising an elevated hopper, a cut-off acting therein, an adjustable measuring chamber connected with the lower end of the hopper, 105 another cut-off acting to open and close the bottom of the measuring chamber, a delivery tube depending from such chamber, means for opening and closing the respective cut-offs in reverse order, a folder and spreader plate by which one end flap is folded and the side flaps spread outwardly at the top of a filled carton as its holder is advanced, a kick-lever with link connections and a wheel connected therewith which 110 wheel contacts with one end of the moving carton holder and operates said lever to fold the other top end flap, a spring by which the kick-lever is drawn back to a normal position when the said wheel passes off the carton holder, means for applying glue to 115 said spread flaps, means for folding said glued flaps, and means for ejecting the filled and sealed cartons from their holders.

10. In a machine for filling and sealing 120

cartons, the combination of an elongated bed and supports therefor, a guide frame supported over said bed parallel therewith and extending longitudinally thereof on both 5 sides and provided with longitudinal grooves, a sprocket wheel, a vertical shaft for the same, supported in adjustable bearings upon the bed and frame adjacent one end thereof, another sprocket wheel adjacent the other end of the frame, a vertical shaft for the same extending through a bearing in the bed, an endless sprocket chain 10 connected with said sprocket wheels and supported in the grooves in said frame, a series of equally spaced guide plates loosely 15 fitted into said grooves in the frame and secured to said chain on one side thereof, a series of carton holders attached to the respective guide plates, means for intermittently rotating said second sprocket 20 wheel, means for folding and sealing the bottom flaps of the carton, means for supporting the cartons thus sealed, means for delivering a measured quantity of filling 25 material into the cartons in succession, comprising an elevated hopper, a cut-off acting therein, an adjustable measuring chamber connected with the lower end of the hopper, another cut-off acting to open and close the 30 bottom of the measuring chamber, a delivery tube depending from such chamber, means for opening and closing the respective cut-offs in reverse order, and means for folding and sealing the top flaps of the filled cartons, all while the cartons are intermittently 35 moved above the bed in the same horizontal plane.

11. In a machine for filling and sealing cartons, the combination of an elongated bed and supports therefor, a guide frame composed of two horizontal parallel bars arranged one above the other in vertical alinement, and provided with a longitudinal groove in their facing surfaces, said bars 40 extending longitudinally of the bed on each side thereof and having semi-circular end connections forming a continuous upper and lower guide member, vertical supports for the same secured to each bar and at their lower ends to the bed, two sprocket wheels 45 horizontally disposed, one adjacent each end within said frame, an endless sprocket chain connecting said sprocket wheels, a series of equally spaced vertical guide plates arranged 50 between the upper and lower bars of said frame and fitted loosely within the grooves therein and connected with said sprocket chain, a series of carton holders provided with lugs secured to the respective plates, 55 means for rotating said sprocket wheels intermittently, means for folding the bottom end flaps of a carton and spreading the lower side flaps thereof, means for applying 60 glue to said spread flaps, means for folding said glued flaps, an elongated support for 65

the bottom of the carton thus sealed, means for filling the carton with a measured quantity of filling material, comprising an elevated hopper, a cut-off acting therein, an adjustable measuring chamber connected 70 with the lower end of the hopper, another cut-off acting to open and close the bottom of the measuring chamber, a delivery tube depending from such chamber, means for opening and closing the respective cut-offs 75 in reverse order, and means for folding and sealing the top flaps of the carton after it has been filled.

12. In a machine of the character described, the combination of an endless conveyer, means for imparting an intermittent movement to the same, a series of equally spaced carton holders connected to one side of the conveyer, means for folding one end flap and spreading the side flaps at the bottom 80 of a carton as its holder is advanced, means operated by contact with the moving carton holder for folding the other end flap at the bottom of the carton, means for applying glue to said spread side flaps, means 85 for folding said glued flaps one upon the other, an elongated bearing for the bottoms of the cartons thus folded and sealed, means for discharging a measured quantity of filling material into such cartons in succession, 90 comprising an elevated hopper, a cut-off acting therein, an adjustable measuring chamber connected with the lower end of the hopper, another cut-off acting to open and close the bottom of the measuring chamber, a 95 delivery tube depending from such chamber, means for opening and closing the respective cut-offs in reverse order, means for locking the said first cut-off in a closed position, means for folding one top end flap and 100 spreading the two top side flaps, means for applying glue to said spread flaps, means operated by contact with the carton holder for folding the other top end flap, means for folding the two top glued side flaps, and 105 means bearing upon said folded flaps while the glue is setting or drying.

13. In a machine for filling and sealing cartons, the combination of an elongated bed and supports therefor, a guide frame supported over said bed parallel therewith and extending longitudinally thereof on both sides, a conveyer chain supported in said frame, means for imparting an intermittent horizontal rotation to the same, a series of 115 equally spaced carton holders connected to the chain, means for folding and sealing the bottom end flaps of the cartons as their holders are advanced, means for delivering a measured quantity of filling material into the cartons in succession, means for folding and sealing the top end flaps of the filled 120 cartons, and means for ejecting the filled cartons from their holders, comprising a vertical plunger attached to one end of a 125 130

horizontal arm, a vertical rod to which the other end of said arm is fixed, a link to one end of which the lower end of said vertical rod is pivotally connected, an arm pivotally connected to the other end of said link, a bracket to which the other end of said arm is pivotally connected, a shaft, bearings for the same, a cam keyed to said shaft, a roller pivotally secured upon said arm with which 5 said cam contacts at each revolution of said shaft, means for rotating said shaft, a tubular standard within which said vertical rod is located above the bed of the machine, and a spring surrounding said vertical rod with- 10 in said standard for returning the plunger to its normal position after it has been operated by the action of said cam upon said wheel.

14. In a machine for filling and sealing 20 cartons, the combination of an elongated bed and supports therefor, a guide frame supported over said bed parallel therewith and extending longitudinally thereof on both sides, a conveyer chain supported in 25 said frame, means for imparting an intermittent horizontal rotation to the same, a series of equally spaced carton holders connected to the chain, means for folding and sealing the bottom end flaps of the cartons 30 as their holders are advanced, means for delivering a measured quantity of filling material into the cartons in succession, means for folding and sealing the top end flaps of the filled cartons, and means for ejecting 35 the filled cartons from their holders, comprising a vertical plunger attached to one end of a horizontal arm, a vertical rod to which the other end of said arm is fixed, a link to one end of which the lower end of 40 said vertical rod is pivotally connected, an arm pivotally connected to the other end of said link, a bracket to which the other end of said arm is pivotally connected, a shaft, bearings for the same, a cam keyed to 45 said shaft, a roller pivotally secured upon said arm with which said cam contacts at each revolution of said shaft, means for rotating said shaft, a tubular standard within which said vertical rod is located above the 50 bed of the machine, a spring surrounding said vertical rod within said standard for returning the plunger to its normal position after it has been operated by the action of said cam upon said wheel, and a pusher con- 55 tacting with the filled and sealed cartons after they are ejected from their holders.

15. In a machine for filling and sealing 60 cartons, the combination of an elongated bed and supports therefor, a guide frame sup- 65 ported over said bed parallel therewith and extending longitudinally thereof on both sides, a conveyer chain supported in said frame, means for imparting an intermittent horizontal rotation to the same, a series of 70 equally spaced carton holders connected to

the chain, means for folding and sealing the bottom end flaps of the cartons as their holders are advanced, means for delivering a measured quantity of filling material into the cartons in succession, means for folding 70 and sealing the top end flaps of the filled cartons, means for ejecting the filled cartons from their holders onto the bed of the machine, and means for carrying them forward, comprising a pusher secured to the 75 upper end of a vertically disposed arm extending through a slot in the bed and pivotally connected at its lower end to a bracket, a transverse shaft, bearings for the same, means for revolving said shaft, a cam keyed 80 to said shaft, a roller pivotally secured to said arm with which said cam contacts at each revolution of said shaft throwing said arm forward on its pivot, and a spring attached at one end to said arm and at its 85 other end to the bed, to draw said arm back when the cam passes off said wheel.

16. In a machine of the character described, the combination of an endless conveyer, means for rotating the same intermittently in one horizontal plane, a series of 90 equally spaced carton holders attached to said chain, means for folding and sealing the bottom flaps of the cartons as their holders are advanced, means for delivering a measured quantity of filling material into the cartons, comprising an elevated hopper, a measuring chamber rotatably connected with the bottom of the hopper and exteriorly threaded on its lower tubular portion, a 95 tubular member interiorly threaded into which the threaded portion of the measuring chamber is screwed, a vertical tube attached to and communicating with the interior of said tubular member, a cut-off acting through 100 a slot in one side of said hopper, another cut-off acting between the measuring chamber and said tubular member, and means for actuating said cut-offs in reverse order.

17. In a machine of the character described, the combination of an endless conveyer, means for rotating the same intermittently in one horizontal plane, a series of 110 equally spaced carton holders attached to said chain, means for folding and sealing the bottom flaps of the cartons as their holders are advanced, means for delivering a measured quantity of filling material into the cartons, comprising an elevated hopper, a measuring chamber rotatably connected 115 with the bottom of the hopper and exteriorly threaded on its lower tubular portion, a tubular member interiorly threaded into which the threaded portion of the measuring chamber is screwed, a vertical tube attached to and communicating with the interior of said tubular member, a cut-off acting through 120 a slot in one side of said hopper, another cut-off acting between the measuring chamber and said tubular member, and means for actuating said cut-offs in reverse order.

18. In a machine of the character described, the combination of an endless conveyer, means for rotating the same intermittently in one horizontal plane, a series of 125 equally spaced carton holders attached to said chain, means for folding and sealing the bottom flaps of the cartons as their holders are advanced, means for delivering a measured quantity of filling material into the cartons, comprising an elevated hopper, a measuring chamber rotatably connected with the bottom of the hopper and exteriorly threaded on its lower tubular portion, a tubular member interiorly threaded into which the threaded portion of the measuring chamber is screwed, a vertical tube attached to and communicating with the interior of said tubular member, a cut-off acting through a slot in one side of said hopper, another cut-off acting between the measuring chamber and said tubular mem- 130

ber, means for actuating said cut-offs in reverse order, a funnel supported below said vertical tube in alinement therewith, and means for raising and lowering the same.

- 5 18. In a machine of the character described, the combination of an endless conveyor, means for rotating the same intermittently in one horizontal plane, a series of equally spaced carton holders attached
10 to said chain, means for folding and sealing the bottom flaps of the cartons as their holders are advanced, means for delivering a measured quantity of filling material into the cartons, comprising an elevated hopper,
15 a measuring chamber rotatably connected with the bottom of the hopper and exteriorly threaded on its lower tubular portion, a tubular member interiorly threaded into which the threaded portion of the
20 measuring chamber is screwed, a vertical tube attached to and communicating with the interior of said tubular member, a cut-off acting through a slot in one side of said hopper, another cut-off acting between the
25 measuring chamber and said tubular member, means for actuating said cut-offs in reverse order, and means for locking said first cut off in a closed position.
19. In a machine of the character
30 described, the combination of an endless chain, means for imparting an intermittent horizontal rotation to said chain, a series of equally spaced carton holders connected to the chain, means for folding and sealing
35 the bottom end flaps of the cartons as their holders are advanced, and means for delivering a measured quantity of filling material into the cartons, comprising an elevated hopper provided with a transverse
40 slot in one side, a cut-off plate adapted to slide through said slot, a horizontal rod connected to said plate, a wheel attached at the other end of said rod, a vertical shaft, a cam keyed to said shaft in alinement with
45 said wheel, a spiral spring surrounding a portion of said rod, a measuring chamber rotatably connected with the bottom of said hopper and provided with an exterior screw thread on its lower end, a tubular in-
50 teriorly threaded member into which the lower threaded end of said chamber is screwed, said member having a flanged bottom, a tube having a flanged upper end secured to the flanged bottom of the other
55 member, there being a longitudinal groove in the upper surface of the flange on one side of said tube, a cut-off plate adapted to slide in said groove and extend across the interior of said tubes, a horizontal rod
60 connected to said plate, passing through a slotted bearing, a plate secured to the other end of said rod provided with a longitudinal slot through which said vertical shaft

passes, a wheel pivoted to the end of said plate, a cam keyed to said shaft and contacting with said wheel, when said shaft is rotated, a hub keyed to said rod, a spiral spring surrounding said rod between said hub and bearing, and means for rotating said vertical shaft. 70

20. In a machine of the character described, the combination of an endless chain, means for imparting an intermittent horizontal rotation to said chain, a series of equally spaced carton holders connected to the chain, means for folding and sealing the bottom end flaps of the cartons as their holders are advanced, and means for delivering a measured quantity of filling material into the cartons, comprising an elevated hopper provided with a transverse slot in one side, a cut-off plate adapted to slide through said slot, a horizontal rod connected to said plate, a wheel attached at the other end of said rod, a vertical shaft, a cam keyed to said shaft in alinement with said wheel, a spiral spring surrounding a portion of said rod, a measuring chamber rotatably connected with the bottom of said hopper and provided with an exterior screw thread on its lower end, a tubular interiorly threaded member into which the lower threaded end of said chamber is screwed, said member having a flanged bottom, a tube having a flanged upper end secured to the flanged bottom of the other member, there being a longitudinal groove in the upper surface of the flange on one side of said tube, a cut-off plate adapted to slide in said groove and extend across the interior of said tubes, a horizontal rod connecting to said plate, passing through a slotted bearing, a plate secured to the other end of said rod provided with a longitudinal slot through which said vertical shaft passes, a wheel pivoted to the end of said plate, a cam keyed to said shaft and contacting with said wheel when said shaft is rotated, a hub keyed to said rod, a spiral spring surrounding said rod between said hub and bearing, means for rotating said vertical shaft, an agitator rotatably suspended within said hopper, a bevel gear fixed to the top of the agitator shaft, a horizontal rod rotatable in bearings supported by the top of the hopper and provided with a bevel gear on one end meshing with said gear on the agitator shaft, and a bevel gear fixed to its other end meshing with a bevel gear fixed to the top of said vertical shaft, whereby said agitator is operated by the rotation of said vertical shaft.

Signed by me this 6th day of April,
1918.

GILBERT F. HELSON.
